UNITED STATES PATENT OFFICE.

HENRY P. FISKE, OF WATERBURY, CONNECTICUT, ASSIGNOR TO THE AMERICAN RING COMPANY, OF SAME PLACE.

DIE USED IN MAKING DECORATIVE NAILS.

SPECIFICATION forming part of Letters Patent No. 396,200, dated January 15, 1889.

Application filed June 25, 1888. Serial No. 278,122. (No model.)

To all whom it may concern:

Be it known that I, HENRY P. FISKE, of Waterbury, in the county of New Haven and State of Connecticut, have invented an Improvement in Dies for Making Decorative Nails, of which the following is a specification.

Upon reference to my patent, No. 388,126, granted August 21, 1888, a description will be found of a nail having a wire shank and an ornamental sheet-metal head. In this the wire shank is made from wire that is fed in and cut off in such a manner that a point is formed upon each nail immediately before it is delivered from the machine, and simultaneously a neck is formed upon the end of the wire, so as to receive a sheet-metal head, and the blank from which the sheet-metal head is formed is made circular and has upon one side a cup-shaped projection that receives the head of the wire shank, and the metal at the edge of the cup is closed around the neck upon such wire shank.

In my present invention I make use of a wire shank, and I supply in between the dies a circular blank with the cup or teat formed thereon; and my present invention relates to the peculiarity of the dies, hereinafter set forth, for shaping up the sheet metal of the head. In dies that have been made use of for this purpose there has been an opening between the convex die and the concave die or matrix, and in stamping the sheet metal up into shape it has often been found that the edge of the ornamental sheet-metal head is not straight and true, but more or less thinned or corrugated at the edge where the metal is forced out between the die and the matrix. I construct my dies to prevent this difficulty and to insure a smooth flat edge to the sheet metal of the head, so that the fabric or material into which the nail is driven will not be cut or injured by any roughness or inequality at the edge of the sheet metal of the head.

In the drawings, Figure 1 is a longitudinal section of the die and matrix. Fig. 2 is a face view of the die. Fig. 3 is a longitudinal section representing the nail-head in a modi-

fied shape, and Fig. 4 is an end view of the die.

The die *a* is made at its end of the proper shape for the interior of the sheet-metal head, and it is perforated longitudinally for the passage of the wire *c*, that forms the shank of the nail, and there is a recess at the end of the die for the reception of the edges of the cup or teat upon the inside of the sheet-metal blank, and by which the edges of the cup or teat are pressed tightly around the neck near the end of the wire *c* as the sheet metal of the nail-head is struck up into the matrix.

The matrix *d* is provided with the depression *b'*, of the proper shape for the exterior of the ornamental sheet-metal nail-head.

The diameter of the face of the die *a* at the offset or shoulder 2 corresponds to the internal diameter of the depression in the matrix *b*, and the nail-head blank with the teat thereon corresponds in diameter, or nearly so, to the shoulder 2 upon the face of the die *a*. Hence the sheet-metal blank can be passed into the matrix *b* and pressed therein by the action of the die *a*, the pressure causing the sheet metal to spread and fill the cavity between the end of the die and the surface of the matrix, and the metal cannot escape at the edges of the blank, because the shoulder 2 on the die *a* fits tightly within the matrix, and when the pressure is applied the blank is pressed up to shape and the edges of the teat or cup closed tightly around the neck, and the material is consolidated and spread toward the face of the shoulder 2, so that the edge of the ornamental head *d* is true and smooth, regardless of any peculiarity in the shape of the head itself, and it will be seen by reference to Fig. 2 that the head may be conoidal or it may be a segment of a globe with a narrow flange, 1, as seen in Fig. 1, in all instances the metal being so confined that the proper shape is secured for the sheet-metal nail-head, and at the same time the metal being confined cannot spread outwardly, and the cup or teat is more reliably closed than could heretofore be done around the neck and head of the wire that forms the shank of the nail. After the sheet-metal

head has been pressed up to shape and fastened upon the end of the wire *c* the dies are opened and the wire fed along and cut off, as in my aforesaid patent.

5 I claim as my invention—

The die *a*, having a hole for the passage of a wire which forms the shank of the nail, said hole opening into a conical recess in the die to form the cup or teat that connects the sheet-metal head to the shank, and said die having a circular shoulder or offset at 2, in combination with the matrix *b*, having a recess corresponding in shape to the exterior of the

sheet-metal nail-head, and a circular opening into which the shoulder 2 fits tightly, so as 15 to confine the sheet metal of the nail-head and render the head true and perfect by the pressure of the die upon the same, the metal being confined between the die and matrix, substantially as set forth. 20

Signed by me this 21st day of June, A. D. 1888.

HENRY P. FISKE.
